UNITED STATES PATENT OFFICE.

EDWARD C. HOLMES, OF LUDLOW, KENTUCKY.

CURTAIN FOR VESTIBULE-CARS.

No. 820,195.

Specification of Letters Patent.

Patented May 8, 1906.

Application filed December 21, 1905. Serial No. 292,876.

To all whom it may concern:

Be it known that I, EDWARD C. HOLMES, a citizen of the United States, residing in Ludlow, county of Kenton, and State of Kentucky, have invented certain new and useful Improvements in Curtains for Vestibule-Cars, of which the following is a full, clear, and exact description, reference being had to the accompanying drawings, forming part of this specification.

It has long been customary in the operation of vestibule-cars on railroads to provide a curtain on each side of the vestibule passage-way to cover up the flexible folds and the contact-surfaces of the diaphragm-frame incidentally to keep out the dust and dirt, but more especially to prevent injury to passengers and others in the movement of the diaphragm-plates on each other under the shifting of the cars when in motion in rounding curves and the like. In order that these curtains may not be torn or destroyed when the cars are separated by reason of the carelessness of an employee in failing to unhook the curtains, devices have been employed to release the retaining-hooks automatically as the cars are pulled apart.

It is the purpose of my invention to provide a certain novel construction, to be herein particularly pointed out and claimed, whereby when the curtains are drawn out beyond their normal point of extension the retaining-hooks shall be automatically released.

The principle of my invention, which will be hereinafter specifically described, consists in providing what may be called a "working" length and a "releasing" length for the curtain and in arranging a hook which under normal conditions shall be kept in fixed position to hold the curtain; but as soon as the curtain shall be drawn out beyond its working length by the cutting apart of the cars, and before the curtain is completely unwound from its roller shall be released, so that the curtain may be wound up by the shade-roller spring without damage.

In the drawings, Figure 1 is a side elevation of the inside of the vestibule of two vestibule-cars with the protecting-curtain in place. Fig. 2 is a horizontal section of same. Fig. 3 is a front elevation of my improved catch with the curtain-handle in place. Fig. 4 is a horizontal section of same. Fig. 5 is a similar horizontal section showing the curtain in its released position. Fig. 6 is a de-

tail horizontal section of the roller end of the curtain drawn out to its releasing length. Fig. 7 is a similar section under normal conditions. Fig. 8 is a vertical section of a portion of the curtain, showing the releasing-
60 strip.

1 and 2 represent half of the vestibules of two cars 3 and 4, 5 and 6 being the platform-doors covering the steps, and 7 and 8 the exit-doors from the vestibule. 9 and 10 are 65 the diaphragm-frames, and 11 and 12 the usual rubber diaphragm folds, and 13 and 14 two of the diaphragm-posts for the two cars on one side of the passage-way.

Mounted vertically in the diaphragm-post 70 13 is the curtain-roller 15, upon which is wound the curtain 16, which passes out through a slot 17 in the diaphragm-posts, the usual springs on the roller 15 being provided to send up the curtain when it is not in use. 75 The vertical outer edge of the curtain is provided with a tube or rod 17, which is usually hollow and around which the curtain is bound to protect the outer edge. Clamped around this tube 17 and held by screws 18 18 80 is a rectangular handle 19.

All of the parts so far described are of the usual and ordinary construction, and it is usual to provide on the vestibule-posts 14 a fixed hook, over which the handle is passed to 85 hold the curtain in place.

Instead of providing a small rectangular handle and a fixed hook, which necessitates the unhooking of the handle to allow the curtain to wind up when the cars are cut apart, 90 I provide as follows: A suitable recess 20 is formed in the diaphragm-post 14, which recess is covered and protected by the slotted escutcheon-plate 21. Pivoted on the vertical pin 22 in this recess is the catch 23, provided with two prongs 24 25. The side arms of the handle 19 are recessed and slotted on their inner edge and carry the bar 26 to slide therein, coiled springs 27 being mounted in the recess and bearing against the ends 28 of 100 this bar, so as normally to hold it in its outer position, as shown in Fig. 3. Secured on this bar is a flexible strip of tape 29 or other suitable material. This flexible strip 29 runs 105 back along the curtain material and is securely looped and fastened around the curtain-roller 15. This strip 29 is not as long as the curtain itself, and at its inner end the curtain is cut away around the roller 15, so as to permit the band 29 to be secured loosely 110

around the roller, as shown at 30 in Fig. 6, to permit the roller to turn on the loop 30 and to prevent any strain that may be applied to the strip 29 from in any way causing a strain 5 on the curtain. This strip 29 passes through a slot 31 in the tube or rod 17, and a strip of curtain material 32 is preferably provided, so as to inclose the strip loosely on the curtain. The length of the curtain is such that when 10 drawn out so that the flexible strip 29 has reached its full length of extension there will still be one or more turns of the curtain material around the roller 15.

In order to secure the curtain in place, the 15 outer bar of the handle 19 is placed over the prong 24 of the catch 23 and the sliding bar 26 is placed under the prong 25. It will be evident that when the curtain is thus secured over the catch 23 and there are a number of 20 turns of the curtain material and flexible strip 29 around the roller 15, as shown in Fig. 7, the curtain will be securely locked in place, the bar 26 under the prong 25 of the catch rigidly holding the catch in position, as 25 shown in Fig. 4, with the bar 26 pressed against the escutcheon-plate 21, and it will be also evident that under normal conditions the pull on the curtain in the shifting of the cars in rounding curves and the like will only 30 tend to cause the catch to maintain a firmer hold on the curtain-handle. A slot 33 is provided in the escutcheon-plate to allow the catch to turn back into the recess 20 into the position shown in dotted lines in Fig. 4, and 35 it will be evident that if the cars are cut apart and the curtain unwound from the roller the strain as the curtain is unwound will come first on the flexible strip 29, and thereupon the bar 26 will be drawn from under the 40 prong 25 and that the sharper the pull the more quickly the bar will be drawn out and that thereupon before the curtain has a chance to unwind fully the front bar of the handle 19 will pull back the catch and slide off of the 45 prong 24 and the curtain be released to be wound up by the roller without any damage thereto. In order to return the catch to its normal position, I provide a light coiled spring 34 on the pivot-pin 22, bearing on the 50 catch.

As it may happen that some of the cars equipped with my device will not be provided with the proper catches, I provide the lever 35, pivoted on the pin 36, which can be 55 thrown up in front of the catch 23 to convert it into a fixed catch. Normally this catch

will stand in a position (shown in dotted lines in Fig. 3) out of the pathway of the machine.

Having thus described my invention, what I claim as new, and desire to secure by Letters Patent, is—

1. The combination with a curtain-roller and curtain, of a handle for holding the curtain, with a releasing device for the handle, and connection therefor with the curtain-roller of shorter length than the curtain, whereby upon drawing out the curtain beyond its normal extension the releasing device will be actuated. 60

2. The combination, with a curtain-roller and curtain, of a handle for holding the curtain, with a releasing device for the handle, and connection therefor with the curtain-roller of shorter length than the curtain, and a pivoted catch to retain the handle, held in 65 operation by said releasing device, until said device is actuated by drawing out the curtain beyond its normal extension. 70

3. The combination with a curtain-roller and curtain, of a handle for holding the curtain, a bar slidably mounted on said handle, and flexible connection therefor, with the curtain-roller of shorter length than the curtain, and a pivoted catch with prongs in opposite 75 direction, one prong engaging the handle and the other the sliding bar whereby said handle is locked until the bar is withdrawn. 80

4. In combination with abutting car-vestibules, with a curtain-roller and curtain secured on one car, and a pivoted catch for 85 holding the curtain secured on the other car, of means for locking the catch in operative position, and a flexible strip of shorter length than the curtain connecting said locking 90 means with said curtain-roller for shifting 95 said locking means to release the catch when the cars are cut apart.

5. In combination with abutting car-vestibules, with a curtain-roller and curtain secured on one car, and a handle for the curtain, of a pivoted catch for engaging said handle secured to the other car, sliding bar mounted on the handle engaged by said catch to hold same in operative position, and a flexible strip of shorter length than the curtain connecting said sliding bar with the curtain-roller to shift said locking-bar to release 100 said catch when the cars are cut apart. 105
